UNITED STATES PATENT OFFICE.

ROBERT THOMPSON, OF SAN FRANCISCO, CALIFORNIA.

BOOT.

SPECIFICATION forming part of Letters Patent No. 254,071, dated February 21, 1882.

Application filed August 2, 1881. (No model.)

To all whom it may concern:

Be it known that I, ROBERT THOMPSON, of the city and county of San Francisco, State of California, have invented certain new and 5 useful Improvements in Boots; and I do hereby declare that the following is a full, clear, and exact description thereof, reference being had to the accompanying drawings.

My invention relates to a seamless-foot boot 10 having the entire front of the foot and leg and the quarters cut in a single piece on parallel perpendicular lines on either side extending down to the ankle-bone and then on approximately horizontal lines around the heel, as will 15 be hereinafter more fully set forth.

The accompanying drawings form a part of this specification.

Figure 1 is a side elevation of my improved boot. Fig. 2 is a back view of my improved 20 boot.

Let A represent the upper, B the quarter, C the front part of the leg, and D the rear part of the leg, of a boot. The entire front of the boot, including the upper and the leg portion, 25 together with the quarters, is formed of one piece of leather, cut in parallel perpendicular lines down the sides to the height of the ankle-bone and thence on that height around the heel. The upper front of the leg and two quarters I cut in one single piece without side or 30 eye seams below the ankle-bone. I then shape the upper and unite the edges of the two quarters at the back of the heel by stitching or otherwise. The rear part, D, of the leg extends 35 down to the top of the counters, and its lower edge is stitched to the upper edge of the quarters, and its side edges are united to the front part, C, by side seams in the usual way. The

side seams, however, extend downward only to the quarters, as shown, or, if preferred, the 40 back part can extend down to the heel, so as to cover the back seam, and thereby strengthen it. In this case it is also stitched to the top of the counter, and its side edges are stitched either to the side of the boot or to the inside 45 lining. The back seam, that unites the edges of the quarters behind the heel, I then cover with a stay or narrow strip of leather, F, which extends up to a considerable distance above the counter, so as to cover the cross-seam. 50 This covering strip is stitched or otherwise secured to the counter and lower part of the leg where it extends above the counter.

Having thus described my invention, what I claim, and desire to secure by Letters Patent, 55 is—

1. In a boot, the front thereof and quarters cut in a single piece on parallel perpendicular lines down the sides to the height of the ankle-bone and thence at that height around the heel, 60 in combination with the rear portion, D, as set forth.

2. In a boot, the upper, front of the leg, and quarters formed in a single piece cut on parallel perpendicular lines down the sides to the 65 height of the ankle-bone and thence on that level around the heel, in combination with the rear leg portion, D, and stiffening-piece F, extending up the leg above the quarters, as set forth. 70

In witness whereof I have hereunto set my hand and seal.

ROBERT THOMPSON. [L. S.]

Attest:

L. MEININGER,
W. F. CLARK.
